UNITED STATES PATENT OFFICE.

PAUL W. FENTON, OF NEW YORK, N. Y.

OIL CONTAINER AND DISPENSER.

Application filed August 10, 1925. Serial No. 49,168.

The invention relates to containers for oils and like liquids and more particularly to containers of such a character that there may be conveniently associated therewith a dispensing pump or like member for removing the contents therefrom. It has for its object to provide a container which is so constructed that it will be impracticable to refill the same or replace the contents thereof with an inferior oil. A further object of the invention consists in providing a rugged and substantial construction of container of this type although withal inexpensive.

The nature of the invention, however, will best be understood when described in connection with the accompanying drawings, in which—

Fig. 1 is a vertical section thru the novel container.

Figs. 2 and 3 are fragmentary sectional views illustrating respectively the mounting of the upper and lower knockout members.

Fig. 4 is a vertical section thru the container and suction tube of the dispensing pump, showing the latter inserted into the container for dispensing the contents thereof.

Fig. 5 is a fragmentary vertical section showing the manner of attaching the pump to the guide tube and the means for venting the container.

Fig. 6 is a fragmentary elevation, partly in section, of the locking device for the suction tube.

Referring to the drawings, 10 designates a can or container suitably constructed, as of sheet metal, to provide a receptacle of a predetermined capacity, such as a five gallon oil can. Said receptacle is provided at the top with a filling opening 11 through which the contents are to be inserted and after which the can is to be sealed in manner hereinafter set forth. In sealing this opening 11, reference being had to Fig. 2, use is made of an annular knockout holding member 12 which is arranged to be soldered over the edge of the said opening 11; and to said annular disk in turn is secured, by crimping over the edge and suitably closing with a sealing compound, a screw threaded member 13 which is in effect a continuation of a tube 14. The latter extends into the receptacle 10 from its top and substantially to the bottom thereof; and is provided at its lower end with an enlargement 15 affording a shoulder 16. The bottom of said

enlargement may be guided and held in a surrounding open guide 17 secured to the bottom of the receptacle. The lower open end of the enlargement, furthermore, is sealed by a knockout sealing disk 18, as by turning the bottom edge of the enlarged portion over the circumference of said disk, Fig. 3; and the tube at its upper end may be closed as, for example, by screw disk cap 19 fitted thereover to prevent entrance of foreign matter into the interior of the tube. The latter, normally, is thus sealed both at top and bottom and lies within the body of the contents of the receptacle.

The diameter of the tube 14 proper is such as to receive and guide with a snug fit the suction tube 20 of the dispensing apparatus 21, which may be in the nature of an ordinary piston type measuring pump with delivery hose 22 attached thereto and operated from a crank handle 23. This suction tube, however, is provided at its lower end with a knockingout edge 25 and slightly above same with spring latches 26 normally urged outwardly from the tube walls, to which they are pivoted. Thus, when the suction tube is inserted a sufficient extent into the tube 14, its lower edge 25 will engage the disk 18 and upon further insertion knock the same out and establish communication between the suction tube and the interior of the receptacle so that the contents may be removed therefrom. As this suction tube is inserted, moreover, the latches spring out therefrom under the shoulder 16 of the enlarged portion of said tube 14 as they pass by the same, so that it is no longer possible to withdraw the suction tube and separate the dispensing mechanism from the container. This can be accomplished only by forcibly withdrawing the upper knockout member 13 thru the requisite pull thereon by the dispensing apparatus which will thereby sufficiently mar the container to prevent its further use. After the suction tube and surrounding tube have thus been removed with the knockout disk 13, the latches 26 are rendered accessible and may be closed within the walls of the suction tube to permit the latter to be withdrawn thru the tube 14 and thus render the dispensing apparatus available for subsequent use with further and full containers.

In dispensing the contents of the container it is, of course, necessary that a vent to the interior of said container be provided

and suitable provision therefor may be made as thru the screw threaded portion 30 at the top of the tube 14. For example, a screw 31 with an axial bore 32 may be mounted 5 in the body portion 33 of the dispensing pump 21 fitting over the threaded end 30; and is adapted to pass thru said body portion to cut thru the said threaded portion. The interior of the container is thus placed 10 into communication with the atmosphere thru the axial opening 32 permitting the contents to be dispensed thru hose 22 as the pump 21 is operated by the crank handle 23. It is to be noted, also, that the screw 31 15 serves to lock the tube 14 to the pump 21 so that in withdrawing the same, after the contents have been exhausted, the strain will not be entirely on the latches 26 in pulling out the knockout disk 13.

20 I claim:—

1. The combination with a receptacle containing liquid, and an access member extending therein, provided with a seal below the surface of the contained liquid and unit- 25 ed to the receptacle thru a weakened portion; of a dispensing member for said liquid, and having means for automatically uniting itself to the access member in being inserted therein, and means carried by the 30 dispensing member to then break the seal to establish communication between itself and the receptacle.

2. The combination with a receptacle containing liquid, and a tube mounted therein 35 and sealed off normally from said liquid and extending from the top substantially to the bottom of the receptacle; of a dispensing member having a suction tube adapted to fit within the first-named tube and to open the same at the bottom to afford communication between the contents of the 40 receptacle and the said suction tube.

3. The combination with a receptacle containing liquid, a tube mounted therein and 45 extending from the top substantially to the bottom of the receptacle, and a knockout disk at the lower end of the tube normally sealing the tube from said liquid; of a dispensing member having a suction tube adapted to fit within the first-named tube and to engage the knockout disk to open the tube at the bottom for affording communication between the contents of the receptacle 50 and the said suction tube.

55 4. The combination with a receptacle containing liquid, and a tube mounted therein and sealed off normally from said liquid and extending from the top substantially to the bottom of the receptacle; of a dispensing member having a suction tube adapted to fit within the first-named tube and to open the same at the bottom to afford communication between the contents of the 60 receptacle and the said suction tube, and 65 means movable relatively to said suction

tube for locking the same to said first-named tube.

5. The combination with a receptacle containing liquid, and a tube mounted therein, extending substantially to the top of the receptacle, having an enlarged portion at its lower end and the bottom of said portion being closed to seal said tube normally from said liquid; of a dispensing member having a suction tube adapted to fit within the first- 75 named tube and to open the closure member at the bottom of the enlarged portion to afford communication between the contents of the receptacle and the said suction tube; and means on said suction tube to extend 80 within the enlarged portion of the first-named tube as the suction tube is inserted therein and to prevent its withdrawal.

6. The combination with a receptacle containing liquid, a knockout member at the 85 top thereof, and a tube secured to said knockout member and mounted in the receptacle and sealed off normally from said liquid; of a dispensing member having a suction tube adapted to fit within the first- 90 named tube and to open the same at the bottom to afford communication between the contents of the receptacle and the said suction tube, said dispensing member having means thereon to engage the said first-named 95 tube whereby in withdrawing the dispensing member the said first-named tube and its knockout member are removed therewith as a unit.

7. The combination with a receptacle containing liquid, a tube mounted therein having an enlarged portion at its lower end, a knockout member closing said lower end to seal off normally said tube from said liquid, and a knockout member at the top of the 100 receptacle to which the upper end of said tube is attached; of a dispensing member having a suction tube adapted to fit within the first-named tube and to break out the knockout disk at its lower end, and means 105 on said suction tube to extend within the enlarged portion of the first-named tube as the suction tube is inserted therein and prevent its withdrawal therefrom, whereby in withdrawing the dispensing member the 110 said first-named tube and its upper knockout member are removed therewith as a unit.

8. The combination with a receptacle containing liquid, a tube mounted therein having an enlarged portion at its lower end, a knockout member closing said lower end to seal off normally said tube from said liquid, and a knockout member at the top of the 115 receptacle to which the upper end of said tube is attached; of a dispensing member having a suction tube adapted to fit within the first named tube and to break out the knockout disk at its lower end; and spring- 120 urged latches carried by said suction tube urged to extend within the enlarged portion of the 125 130

first-named tube as the suction tube is inserted therein and prevent its withdrawal therefrom, whereby in withdrawing the dispensing member the said first-named tube 5 and its upper knockout member are removed therewith as a unit.

9. The combination with a receptacle containing liquid, a knockout member at the top thereof, and a tube secured to said 10 knockout member and mounted in the receptacle and sealed off normally from said liquid; of a dispensing member fitting over

the top of the first-named tube and having a suction tube adapted to fit within the first-named tube and to open the same at the 15 bottom to afford communication between the contents of the receptacle and the said suction tube; a screw having an opening there- thru, and adapted to pass thru said dispens- ing member and the first-named tube to vent 20 said container as well as to lock the dispensing member to the said first-named tube.

In testimony whereof I affix my signature.

PAUL W. FENTON.
